TELEGRAPH KEYBOARD TRANSMITTER

Walter J. Zenner, Des Plaines, Ill., assignor to
Teletype Corporation, Chicago, Ill., a corpora-
tion of Delaware

Application May 28, 1949, Serial No. 95,964

5 Claims. (Cl. 178—17)

1

The present invention pertains to telegraph transmitters and more particularly to telegraph transmitters controllable from a manually operated keyboard.

The primary object of the invention is to provide a simple, compact and efficient apparatus for transmission of telegraph signals at very high speeds.

Another object of the invention is to provide in a transmitter, a rocking contact arrangement for generating accurate chatter-free signals.

A further object of the invention is to provide a keyboard operated device wherein the key action is smooth, uniform and light to the touch.

Briefly, the transmitting portion of the arrangement according to the present invention, embodies a cam drum having a series of cam projections arranged helically to effect through a corresponding series of interponents, which are settable permutably by a novel keyboard structure, the operation of a transfer mechanism to vibrate a transmitting contact mechanism to distribute the signal impulses over the signal line. The transmitting contact mechanism is of the type disclosed in copending application, Serial No. 70,730 filed January 13, 1949, by W. J. Zenner.

The foregoing and other objects of the invention will be more apparent in the following detailed description of the invention when taken in conjunction with the accompanying drawings, in which:

Fig. 1 is a fragmental plan view showing essential elements of the keyboard transmitter according to the invention;

Fig. 2 is a front elevational view, partly in section, of the device shown in Fig. 1;

Fig. 3 is a sectional view taken on line 3—3 of Fig. 1;

Fig. 4 is a perspective view of the transfer bail for operating the rocking contact mechanism;

Fig. 5 is a perspective view of the transfer bail showing a detent mechanism;

Fig. 5A is a view showing an alternate form of rocking contact mechanism;

Fig. 6 is a transverse cross-sectional view of the apparatus according to the present invention;

Fig. 7 is a fragmentary transverse cross-sectional view showing an alternate form of key lever arrangement;

Fig. 8 is a fragmentary elevational view, partly in section, showing an arrangement for preventing the simultaneous operation of two or more keylevers;

Fig. 9 is a fragmental cross sectional view of

2

the keyboard showing an alternate form of key top;

Fig. 10 is a sectional view taken on line 10—10 of Fig. 9;

Fig. 11 is a sectional view taken on line 11 of Fig. 1, and

Fig. 12 is a fragmental view showing the alternate position of the key lever locking bail.

The present apparatus embodies primarily a base 10 which is provided at its forward portion with a keyboard of the usual form, and which is adapted to house the key levers and the selector mechanisms operated thereby. Mounted on the base are the power drive means, signal generator and related parts which are selectively controlled by the aforementioned selector mechanism. A motor 11 for supplying the power for operating the keyboard transmitter of the present invention is appropriately mounted on the base portion 10 in position to effect the rotation of a single operating shaft 12. All the parts are thus suitably supported in such a manner as to form a compact self-contained unit.

Having reference to Figs. 1 and 6, the base 10 is provided at its front with a keyboard comprising keylevers 12 operated by keys 13. The keylevers or key members 12 are slidably vertically and are guided at one end by a guide comb 14 mounted on a bracket 15. Each of the key members 12 is pivotally articulated at 16 to an associated selector lever 17 mounted pivotally on a common pivot shaft 18 suitably supported on brackets 19 (one at each end) fixed to the base portion 10. A spring 21 distended between a depending portion 22 of lever 17 and the lower end of its associated key member 12 tends normally to bias the lever 17 in a counterclockwise direction and simultaneously to maintain the key member 12 in its upward position. Each of the key members 12 is provided with an upwardly directed portion 23 to which is fitted its individual key top or cap 13. Key caps 13 are provided with individual flange portions 24, and are removably attached to the portions 23 by means of "chin strap" type springs 25.

The key members 12 and selector levers 17 are guided adjacent their points of articulation 16 in slots in a comb bar 26 suitably supported in the main frame 10. Each of the key members 12 has pivotally articulated thereto a depending wedge shaped member 27 (Figs. 6 and 8) adapted to cooperate with a series of balls 28 in such a manner that upon the depression of a key member 12 the wedge member 27 associated therewith functions to shift the balls 28 so as to prevent

the depression of any of the other key members 12 until the previously depressed key member 12 has been released. The displacement of the balls 28 is adjustd by means of an adjusting screw 29. The wedge members 27 and balls 28 are appropriately guided between a pair of guide bars 31 and 32. A space bar 33 is similarly supported on a pair of arms 34, one of which is associated with a selector lever 17.

The leftwardly directed arms of the selector levers 17 (Fig. 6) cooperate with the coded bottom edges of a series of permutation members or code bars 35. As viewed in Fig. 2, the code bars 35 are adapted to be slidably mounted on cross members 36 and 37 supported on brackets 38 and 39 suitably attached to the base 10. The code bars 35 are normally urged rightwardly (as viewed in Fig. 2) by springs 41 and 42 which are associated with alternate ones of the code bars 35, which in the embodiment described is due to lack of clearance between adjacent code bars to accommodate all the springs at the same end. Thus, certain of the code bars 35 are provided with leftwardly directed extensions 43 to which one end of spring 41 is connected, the other end of the spring 41 being attached to a spring anchor rod 44 journaled in brackets 38. Alternate ones of said code bars 35 are provided with depending portions 45 to which one end of spring 42 is attached, the other end of spring 42 being anchored to a rod 46 journaled in brackets 39.

Each of the code bars 35 is provided with a shouldered portion 47 which cooperates with a bail member 48 mounted pivotally on pivot studs 49 and 51 carried in a bracket 50 (Fig. 6). Fixed to bail 48 by means of screws 52 (Fig. 6) is a bracket 53, at the outer end of which is pivotally carried, on pivot 54, a depending lever 55 which is normally urged in a clockwise direction by a spring 56 connected to lever 55 and anchored to bracket 53. The lever 55 is adapted to thrust against a ball bearing member 57 carried on a pivot shaft 58. Lever 55 is also adapted to bear against an adjustable stop screw 59, due to the pull of spring 56. Thus, the springs 41 and 42 tend to urge the code bars 35 rightwardly (Fig. 2) to in turn tend to urge the bail 48 to rotate counterclockwise, but this motion is resisted by the lever 55 bearing against the ball bearing 57.

The adjusting screw 59 is carried on the vertical arm of a lever 61 mounted pivotally on the shaft 58. The horizontal arm of lever 61 cooperates with a lever 62 pivoted at 63 (Fig. 6). Lever 62 is normally biased counterclockwise by a spring 64. At the extremity of its horizontal arm, lever 62 is provided with a shoulder 65 (Fig. 6) which cooperates with a projection 66 of a plate 67 affixed by screws 68 to a locking bail member 69. Bail 69 normally tends to rotate clockwise about a pair of pivot studs 71 (only one shown in Fig. 1) by a spring 72 connected to an extension on plate 67 and anchored suitably to the frame 10.

Each selector lever 17 is provided adjacent its left end (Fig. 6) with a projection 73 which cooperates with the upper flange of the bail 69, so that when a key member 12 is depressed, the associated selector member is rotated clockwise to cause the projection 73 to strike the upper flange of bail 69 to cause the bail 69 to be rotated counterclockwise. The extremity 74 of selector lever 17 is conformed to provide a locking relationship with the shortened lower flange of the bail 69, whereby, upon actuation of one key member 12, the remaining key members are locked against operation, as indicated in Fig. 12.

Upon the actuation of a key member 12, the bail 69 will thus be rotated counterclockwise, and the projection 66 of plate 67 (Fig. 6) will be caused to ride off of the shoulder 65, thereby permitting the spring 64 to rotate the lever 62 in a counterclockwise direction. Thus, lever 62, through its projection 75 (Fig. 6) will cause lever 61 to be rotated clockwise (Fig. 2) to cause the screw 59 to push the lever 55 off of the ball bearing 57. The ball bearing 57 is provided to facilitate a quick release with a minimum of friction. As the lever 55 is thus released against the action of spring 56, the bail 48 is free to be rotated counterclockwise by the springs 41 and 42 acting through the shoulders 47 on the code bars 35. The code bars 35 are thus freed to move rightwardly, unless their respective wards or projections 76 are blocked by an operated selector lever 17.

Associated with the series of code bars 35 is a universal bar 77 (Fig. 11), which is also provided with a spring 41 (or 42), and with a shoulder 47, so that, as the bail 48 is released, the universal bar 77 will be moved rightwardly to permit a projection 78 on the upper edge thereof to cooperate with a clutch release lever 79. Having reference to Figs. 1 and 11, the clutch release lever 79 is associated with a clutch, indicated generally as 80, of the type disclosed in copending application Serial No. 707,176, filed November 1, 1946, by A. N. Nilson et al., now U. S. Patent No. 2,568,249 of September 18, 1951. Clutch 80 is of the single revolution type, and is normally locked against rotation by the release lever 79 which is normally biased clockwise (as viewed in Fig. 11) by a spring 81. Fixed to shaft 12 (Fig. 1) is the driving portion of clutch 80, the driven portion of which is associated with a cam sleeve 82. Therefore, when the universal bar 77 is actuated rightwardly in response to a key operation, its projection 78 will act through a laterally directed flange 83 of release lever 79 to actuate the clutch release lever 79 counterclockwise about its pivot 84 against the tension of spring 81 to remove the lateral portion 85 from the path of the clutch lever 86 (comparable to lever 27 in the copending application), thereby initiating rotation of the clutch 80, and hence the cam sleeve 82. Incidentally, the clutch release lever 79 is comparable to lever 52 in the copending application. However, in the present embodiment the lever 79 is mechanically controlled, while in said copending application the corresponding lever 52 is electromagnetically controlled.

Referring to Figs. 1 and 2, there is operably associated with sleeve 82 at its forward end, an eccentric drive mechanism for resetting the bail 48 and the code bars 35 (including the universal bar 77). Affixed to the bail 48 is a bent plate 87 having a slot 88 engageable by an arm 89 integral with a plate 91 adjustably associated with an eccentric drive member 92 through arms 93 and 94 of said member 92. Adjustment between the members 91 and 92 is effected by inserting a screw driver in the slots 90 or 100, depending upon which direction adjustment is to be made, and by turning said screw driver to achieve the desired adjustment. Then the clamping screws 60 and 70 are tightened to effect a rigid connection between the members 91 and 92. Upon actuation of a key member 12, the bail 48 will be released, as previously described and will rotate counterclockwise until the plate 87 bears against the shoulder 95 of arm 89. Then, after the clutch 80 and the sleeve 82 have been released for rotation, the eccentric 92 associated therewith will function to move the

plate 91 leftwardly (as viewed in Fig. 2) to in turn, through plate 87, rotate the bail 48 clockwise, thereby causing the lever 55, through spring 56, to rest again upon the bearing 57 and causing the lever 61 to assume the position in Fig. 2, preparatory to response to a further actuation of a key member 12.

In Fig. 3 is shown the reset mechanism for restoring the previously actuated lever 62 to its unactuated position, indicated in Fig. 6. It will be recalled that upon actuation of a key member 12, the selector lever 17 associated therewith functioned to rotate the bail 69 counterclockwise, causing the projection 66 thereof to ride off of the shoulder 65 and permitting the lever 62 to respond to the pull of its spring 64. The projection 66 thereafter rests against the edge 95 of lever 62, following the removal of finger pressure from the operated key member 12. A bell crank lever 96 (Fig. 3) is mounted on a pivot 97 carried in the bracket 50 and is provided with a horizontal arm 98 adapted to cooperate with the lever 62. Pivotedly carried at the extremity of the depending arm of bell crank lever 96 is a latch member 99. The bell crank lever 96 also has a vertical projection 101 which cooperates with a stop pin 102 fixed to the bracket 50. The bell crank lever 96 and latch 99 normally assume the dotted line position shown in Fig. 3 under the pull of spring 103, wherein the latch member 99 is unlatched from the extension 104 of bail 48, and the projection 101 is abutting the stop 102.

Now, when a key member 12 is actuated, the bail 48 will be released, as previously described, and will be actuated counterclockwise (under the influence of code bar springs 41 and 42), whereupon extension 104 will engage the latch 99. Then, when the bail 48 is actuated or returned in a clockwise direction by the arm 87 of the eccentric plate 91, the bell crank lever 96 will be rotated clockwise (by the latch 99) to cause the arm 98 to return the lever 62 to the position shown in Fig. 6. In thus returning lever 62, the projection 66 will be freed from the surface 95, and spring 72 will function to rotate the plate 67 and locking bail 69 from the position shown in Fig. 12 to the position shown in Fig. 6. The plate 67 is provided with an arm 105 having an extremity adapted to overlie the latch 99 (Figs. 3 and 6). Therefore, when the plate 67 and bail 69 are thus rotated clockwise by spring 72 (as just described), the arm 105 will strike the latch 99 and disengage said latch 99 from the extension 104 of bail 48, thereby permitting the spring 103 to return the latch 99 and the bell crank lever 96 to the dotted position shown in Fig. 3.

In the present embodiment of the invention, six of the code bars 35 are employed for making permutation code selections according to the well known Baudot code. If desired, a 5 unit or other code may be employed. In the embodiment shown, eight of the code bars 35 are allotted to the transmission of a six-unit code, comprising a bar 35-1 for controlling the start signal, six bars 35-2 to 35-7 inclusive, for controlling the significant code signal impulses, and a bar 35-8 for controlling the stop signal. As viewed in Fig. 2, each of the bars 35 are provided with projections or wards 76 depending from their lower edge to cooperate with the selector levers 17. Upon the operation of a key member 12 in response to which the bail 48 is released for counterclockwise movement, as previously described, the code bars 35 tend to move rightwardly due to the action of springs 75

41 and 42. However, the selector lever 17 associated with the operated key member 12 will have been presented into the path of the wards 76 so that those bars 35 having wards adjacent the operated selected lever 17 will be prevented from moving rightwardly, and those bars 35 having no wards 76 adjacent the operated selector lever 17 will be permitted to move rightwardly. For each selector lever 17, the arrangement of wards 76 is different, so that different bars 35 are permitted to move rightwardly for each key operated selector lever 17.

Each of the code bars 35 is also provided on its upper edge with a shoulder 106 which cooperates with the lower arm of a lever 107. Levers 107 are mounted pivotally on a suitably supported pivot rod 108, and are normally biased counterclockwise by individual springs 109. Levers 107 are normally held in their clockwise position against the action of spring 109 (as shown in Fig. 2) by the shoulders 106 of code bars 35, and when the code bars are permitted to move rightwardly the associated levers 107 are permitted to rotate counterclockwise a predetermined amount under the action of their individual springs 109. Levers 107 are guided by the upper and lower notched flanges of the comb member 111.

Pivottally articulated to the upper arm of each of the levers 107, and also guided in the upper flange of the comb member 111, is an interponent member 110. Each lever 107 and its associated interponent 110 are maintained in cooperative relationship by an individual spring 113, which also normally biases the associated interponent 110 in a clockwise direction. Each interponent 110 is provided with a cam follower portion 114 adapted to cooperate with an individual cam 115. Each interponent 110 is also provided with a pair of marking and spacing abutments 116 and 117, respectively, adapted to cooperate under predetermined conditions with depending flanges or abutments 118 and 119, respectively, of a rocker member 121, mounted pivotally on a pivot shaft 122.

The cam projections on the cams 115 (eight in the present embodiment) are arranged helically, in well known manner, so that upon rotation of said cams, the interponents 110 will be oscillated sequentially. Thus, if a code bar 35 has not been permitted to move rightwardly (because its ward 76 has been blocked by an operated selector lever 17), its associated interponent 110 will remain in the position shown in Fig. 2, with the abutment 116 in register with the flange 118 of the rocker member 121. Then, when the cam 115 is rotated, the interponent 110 associated therewith, will, in predetermined timed relation with the speed of transmission, be actuated counterclockwise so that the abutment 116 thereon will strike or abut the flange 118 (if the rocker member 121 was in its counterclockwise position) to rotate the rocker member 121 clockwise. On the other hand, if a code bar 35 has been permitted to move rightwardly, its associated interponent 110 will be actuated toward the left to bring the abutment 117 in register with the flange 119 of the rocker member 121. Therefore, when the cam 115 is rotated, the interponent 110 associated therewith will be actuated counterclockwise, as before, but now the abutment 117 will abut the flange 119 to rotate the rocker 121 counterclockwise.

Associated with the series of eight cams 115 is a cam 123 which cooperates with the extremity

of arm 124 of a locking bail member 125 mounted on a pivot 126. Bail 125 is provided with a blade 127 which cooperates with the pointed upper extremities 128 of levers 107. The rightward and leftward reciprocating movements of the interponents 110 is controlled by a limiting stop bar 129, suitably slotted to govern the relative movement between abutments 116 and 117, and the flanges 118 and 119, respectively. Normal counterclockwise bias is imparted to bail 125 by a spring 131.

Integral with the rocker member 121 (in the present embodiment) is a lever arm 112 for actuating the contact mechanism indicated generally by the number 132. This contact mechanism 132 is of the type disclosed in the copending application Serial No. 70,730 filed January 13, 1949, by W. J. Zenner, and comprises in the embodiment disclosed herein, a lever arm 133 having a forked extremity 134 adapted to cooperate with a pin 135 carried by the arm 112 of the rocker member 121. In this manner, the arm 112 is pivotally articulated to the arm 133 of the contact mechanism 132. Arm 133 is pivotally mounted on a pivot 136 carried in a bracket 137 secured by screws 138 to a pedestal 139 supported on the base 10. Cooperating in an overcentering manner with a pair of oppositely disposed substantially V-shaped notches 141 on the arm 133 adjacent to the pivot 136 are a corresponding pair of lever arms 142 and 143 pivotally articulated to associated hinge plates 144 and 145, respectively, secured by screws 146 to the pedestal 139. Carried on lever arm 142 is a contact element 147 which cooperates with a contact element 148 fixed to the bracket 137. Similarly, mounted on the lever arm 143 is a contact 149 which cooperates with a contact element 151 fixed to the bracket 137.

In the embodiment of the invention herein described, the contacts 149—151 function as marking contacts, and the contacts 147—148 function as spacing contacts. Thus, positive or marking battery is applied to contact 151, and the terminal 152 is connected to the signal line. Having reference to Fig. 1, the code bar 35—1, which controls the start signal, is invariably actuated rightwardly upon each key operation, due to the absence of wards 76, to close contacts 147—148. However, since the contacts 147—148 are neutral, a spacing signal (of no-current) will be impressed on the line. The code bars 35—2 to 35—7, inclusive, are set permutable according to the presence or absence of wards 76 thereon, in well known manner. The code bar 35—8, which controls the stop signal is invariably prevented from moving rightwardly due to the presence of wards 76 in each key position; that is, associated with each selector lever 17.

Disposed on arm 112 opposite to pin 135 is a pin 153 cooperable with a limiting stop member 154 to control the rocking motion of member 121 (Fig. 5). Having reference to Fig. 4 there is provided on the rocker 121, a member 155 having a depending extremity 156. An overcentering member 157 is provided at one end with a tongue 158 adapted to fit loosely in a suitable aperture in the depending extremity 156 by means of which the member 157 is pivotally articulated to the member 155. The member 157 is also provided at its other end with a tongue (not shown) which fits loosely in a suitable aperture in a detent lever 159 mounted pivotally on a pivot 161. Lever 159 is normally biased counterclockwise (as viewed in Fig. 4) by a spring 162. Member 157

is thus also pivotally articulated to the detent lever 159. With this over-centering arrangement, the rocker member 121 is urged quickly to its clockwise or counterclockwise position and held thereat due to the extension and retraction of spring 162.

A brief description of operation is as follows: Upon the depression of a key member 12, the selector lever 17 will be presented in the path of wards 76 of code bars 35, and at the same time the projection 73 will rotate bail 69 to release lever 62, which, through bell crank 61, will release the bail 48 to permit the springs 41 and 42 to tend to bias code bars rightwardly. At the same time release bar 77 will release clutch 80 for a single revolution. Levers 107 will be unlocked by bail 125 and levers 107 will thereupon assume a clockwise or counterclockwise position in accordance with the setting of the code bars 35. As previously mentioned the start bar 35—1 and stop bar 35—8 will invariably be set to control the start and stop signal impulses, respectively. Interponents 110 will also assume a right or left position according to setting of levers 107 to bring abutments 116 or 117 into alignment with their respective flanges 118 and 119. Then upon continuation of rotation of cam sleeve 82, the cams 115 will oscillate the interponents 110 to, in turn, rock the member 121 to operate the contact mechanism 132 accordingly. At the close of the cycle of rotation of cam sleeve 82 the eccentric drive 91—92 will impart clockwise movement to the bail 48 to thereby restore the code bars 35 to their leftward position, and to restore levers 55 and 62 to their normal rest positions.

There is shown in Fig. 5-A an alternate form of contact arrangement differing somewhat from the contact mechanism 132 (Fig. 2) in principle of operation. In the form of the invention shown in Fig. 2 the contact levers 142 and 143 cooperate in an overcentering manner with a pair of oppositely disposed V-shaped notches 141 in the lever arm 133. In the form of the invention shown in Fig. 5-A there is provided a contact assembly for closing one or the other of two contact pairs wherein the movable contact pair carrier will, upon movement, be fulcrumed about the stationary contact point of the pair to be closed, rather than about an external pivot point, to prevent vibration and chattering.

Having reference to Fig. 5-A, the arm or extension 112 of the rocker member 121 is pivotally connected, through the pin 135, to an operating lever 185 which is connected pivotally to the stem of a T-shaped lever 186. Each of the arms of the T-lever 186 is provided on its underside with a contact point 187 which cooperate respectively with fixed contact points 188 carried on brackets 189. At a point centrally located between the contacts 187, the swingable lever 186 is provided with a V-shaped notch 191 which cooperates with an arm of substantially U-shaped member 192, the other arm of which cooperates with a V-shaped notch 193 in a bracket 194 mounted on the pedestal 139. A spring 195 having one end attached to the member 192 has the other end attached to a spring post 196.

The spring 195 is, thus, so connected that the member 192 will be urged normally in a clockwise direction (Fig. 5-A), urging the contact points 187 toward their associated contact points 188 formed by the upper surface of pins 197. With the notch 191 centrally located, a balanced pressure is exerted with respect to both of the contact points 187. In actual practice the op-

erating lever 185 will normally be held in such a position that only one contact pair 187—188 will be closed at a time. Thus, the operating lever 185 will be in one of its two positions, or moving from one to the other, which causes the T-lever 186 to be positioned in such a manner as to cause one of the contact points 187 to fulcrum about its associated contact point 188 formed by the upper surface of the pin 197. As a change of selection is made in the operating lever 185, the T-lever 186 will be moved from one position to the other, and as the lever 186 is not pivoted about an external point, it will fulcrum about the contact pair which is desired to be closed. In this manner bounce and vibration will be again eliminated.

An alternate form of key arrangement is shown in Figs. 7, 9 and 10, and comprises a plate 163 having integral tab-like portions 164 formed therein, said portions being slotted to form guide means for associated key members 165, which are suitably capped by key tops 166. Key members 165 are suitably formed, depending on the positions of their respective key tops 166 in the key bank, to terminate in an alignment to engage the respective lateral portions 167 of selector levers 168 mounted pivotally on common pivot shaft 169 (analogous to shaft 18 Fig. 6). A space bar 171 is mounted on a pair of vertical bars 172 pivoted to bell cranks 173 which are in turn pivotally mounted on a pivot shaft 174. The vertical arm of bell crank 173 is pivoted to one end of a link 175, the other end of which is connected pivotally to an arm 176 integral to its particular selector lever 168. Each of the selector levers 168 are provided with an arm 177 terminating in a forked end on which is suspended a wedge member 178 (analogous to wedge member 21, Fig. 8), which is adapted to cooperate with a series of balls 179, which function to prevent the depression of more than one key member at a time (as described hereinbefore in connection with Fig. 8). Similar to selector levers 17, the selector levers 168 terminate in extremities 181 conformed to cooperate with bail 69 in like manner.

It is understood that the invention is capable of embodiment in many applications other than that specifically disclosed without departure from the spirit and scope of the invention as defined in the appended claims.

What is claimed is:

1. In a telegraph transmitter, transmitting contacts, contact actuating mechanism therefor comprising a rockable member having a pair of abutments, a signal distributor cam assembly disposed subjacently to said member, a plurality of interponents disposed between said cam assembly and said rockable member, each of said interponents provided with a pair of spaced abutments, respective ones of said abutments on said interponents adapted to coat selectively with its associated abutment on said rocker member, a set of permutation members, instrumentalities associated with said permutation members for controlling the selective positions of said interponents, a bail means for normally restraining selective movement of said permutation members, a series of depressible keys, a corresponding series of selector bars actuated by said keys, said permutation members having coded elements co-operable with said selector bars, means universally controlled by said selector bars, initiating means operably associated with said universally controlled means, said initiating means comprising a first release means operated under the con-

trol of said universally controlled means, and a second release means operated under the control of said first release means, whereby said bail means is released to effectuate the selective movement of said permutation members under the control of said selector bars to impart through said instrumentalities a corresponding setting to said interponents to enable said cam assembly to operate said rockable member to activate said transmitting contacts according to the settling of said interponents, and cam means for subsequently restoring said bail means to normal position.

2. In a telegraph transmitter, transmitting contacts, contact actuating mechanism therefor comprising a rockable member having a pair of abutments, a signal distributor cam assembly disposed subjacently to said member, a plurality of interponents disposed between said cam assembly and said rockable member, each of said interponents provided with a pair of spaced abutments, respective ones of said abutments on said interponents adapted to coat selectively with its associated abutment on said rocker member, a set of permutation members, instrumentalities associated with said permutation members for controlling the selective positions of said interponents, a first bail for normally restraining selective movement of said permutation members, a series of depressible keys, a corresponding series of selector bars actuated by said keys, said permutation members having coded elements co-operable with said selector bars, a locking bail for said selector bars, trigger means operably associated with said locking bail, said trigger means comprising a first trip-off means operated under the control of said locking bail and a second trip-off means operated under the control of said first trip-off means, whereby said first bail is released to effectuate the selective movement of said permutation bars under the control of said selector bars to impart through said instrumentalities a corresponding setting to said interponents to enable said cam assembly to operate said rockable member to activate said transmitting contacts according to the setting of said interponents, and cam means for subsequently restoring said first bail to normal position.

3. In a telegraph transmitter, transmitting contacts, contact actuating mechanism therefor comprising a rockable member having a pair of abutments, a signal distributor cam assembly disposed subjacently to said member, a plurality of interponents disposed between said cam assembly and said rockable member, each of said interponents provided with a pair of spaced abutments, respective ones of said abutments on said interponents adapted to coat selectively with its associated abutment on said rocker member, a set of permutation members, instrumentalities associated with said permutation members for controlling the selective positions of said interponents, a bail means for normally restraining selective movement of said permutation members, a series of depressible keys, a corresponding series of selector bars actuated by said keys, said permutation members having coded elements co-operable with said selector bars, means universally controlled by said selector bars, means on said universally controlled means effective on conformed extremities of said selector bars for fixating said selector bars during each cyclic operation according to the operation thereof, initiating means operably associated with said universally controlled means, said initiating means

comprising a first release means operated under the control of said universally controlled means and a second release means operated under the control of said first release means, whereby said bail means is released to effectuate the selective movement of said permutation members under the control of said selector bars to impart through said instrumentalities a corresponding setting to said interponents to enable said cam assembly to operate said rockable member to activate said transmitting contacts according to the setting of said interponents, and cam means for subsequently restoring said bail means to normal position.

4. In a telegraph transmitter, transmitting contacts, contact actuating mechanism therefor comprising a rockable member having a pair of abutments, a signal distributor cam assembly disposed subjacently to said member, a plurality of interponents disposed between said cam assembly and said rockable member, each of said interponents provided with a pair of spaced abutments, respective ones of said abutments on said interponents adapted to coact selectively with its associated abutment on said rocker member, a set of permutation members, instrumentalities associated with said permutation members for controlling the selective positions of said interponents, a first means for normally restraining selective movement of said permutation members, a series of depressible keys, a corresponding series of selector bars actuated by said keys, said permutation members having coded elements co-operable with said selector bars, means universally controlled by said selector bars, initiating means operably associated with said universally controlled means, said initiating means comprising a trip-off means operated under the control of said universally controlled means and anti-friction release means operated under the control of said trip-off means, whereby said first means is released to effectuate the selective movement of said permutation members under the control of said selector bars to impart through said instrumentalities a corresponding setting to said interponents to enable said cam assembly to operate said rockable member to activate said transmitting contacts according to the setting of said interponents, and cam means for subsequently restoring said first means to normal position.

45 50

5. In a telegraph transmitter, transmitting contacts, contact actuating mechanism comprising a rockable member having a pair of abutments, a signal distributor cam assembly disposed subjacently to said member, a plurality of interponents disposed between said cam assembly and said rockable member, each of said interponents provided with a pair of spaced abutments, respective ones of said abutments on said interponents adapted to coact selectively with its associated abutment on said rocker member, a set of permutation members, instrumentalities associated with said permutation members for controlling the selective positions of said interponents, a bail means for normally restraining selective movement of said permutation members, a series of depressible keys, a corresponding series of selector bars actuated by said keys, said permutation members having coded elements co-operable with said selector bars, means universally controlled by said selector bars, starting means adapted to initiate operation of the transmitter under control of said universally controlled means, said starting means comprising a first release means operated under the control of said universally controlled means and a second release means operated under the control of said first release means, whereby said bail means is released to effectuate the selective movement of said permutation members under the control of said selector bars to impart through said instrumentalities a corresponding setting to said interponents to enable said cam assembly to operate said rockable member to activate said transmitting contacts according to the setting of said interponents, cam means for subsequently restoring said bail means to normal position, and means controlled by said bail means effective during said operation of restoration to condition 30 35 40 said starting means for reoperation.
